UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

BLINDSTITCH SEWING-MACHINE.

1,287,685.

Specification of Letters Patent. Patented Dec. 17, 1918.

Application filed October 3, 1914. Serial No. 864,710.

To all whom it may concern:

Be it known that I, THOMAS J. HAYES, a citizen of the United States, and resident of Roslindale, county of Suffolk, State of Massachusetts, have invented an Improvement in Blindstitch Sewing-Machines, of which the following description, in connection with the accompanying drawing, is a specification, like characters on the drawing representing like parts.

This invention relates to improvements in blind stitch sewing machines for felling and particularly to the presser foot and guide for the superimposed layer of fabric and the position of the same relative to the back of the needle.

In blind stitch felling machines difficulty is frequently experienced in presenting the superimposed layer to the needle because of the tendency of the infolded portion of the relatively elastic superimposed layer to straighten out, and also because of the tendency of the needle in penetrating the superimposed layer to advance the same slightly upon the base layer and thereby cause wrinkles or puckers in the edge of the superimposed layer as it is stitched to the base layer. The latter is especially true in case thin or soft fabric is used in the superimposed layer.

The principal object of this invention therefore is to provide means for positively directing the superimposed layer in such a manner that its edge will be presented accurately to the needle in a path which will permit the needle to penetrate the same without any tendency to feed the superimposed layer forward. In order to accomplish this end I have provided means upon the presser foot for guiding both the upper and under surfaces of the superimposed layer and for causing the folded layer to be curved gently instead of being bent abruptly as the same is presented to the needle.

The needle mechanism for which the improved presser foot is particularly adapted comprises a curved needle oscillating in a plane inclined to the vertical plane of the line of feed of the material and the presser foot is so positioned in respect to the needle that the needle will enter well back of the edge of the superimposed layer and emerge therefrom at a point within the edge or

nearer to the edge than the point at which it penetrates the superimposed layer.

Other objects of the invention will more fully appear from the following description, the accompanying drawing, and will be pointed out in the annexed claims.

In the drawings:

Fig. 1 is a front elevation of a blind stitch sewing machine for felling provided with a needle oscillating in a plane inclined to the vertical plane of the line of feed, which is particularly adapted for use with the improved presser foot hereinafter described.

Fig. 2 is a detail top plan view of the presser foot embodying my invention,

Fig. 3 is a sectional view on lines 3—3 Fig. 2 looking in the direction of the arrow *a—a*,

Fig. 4 is a vertical sectional view through the presser foot on lines 3—3, Fig. 2 looking in the direction of the arrow *b—b*,

Fig. 5 is an underside plan view of the preferred form of presser foot embodying my invention,

Fig. 6 is a front view of the same.

Fig. 7 is a top plan view of the presser foot showing its relation to the needle while the needle is taking a stitch in the superimposed layer,

Fig. 8 is a similar view showing the relation to the presser foot and needle while the needle is taking a stitch in the base layer,

Fig. 9 is an exaggerated transverse sectional view of the presser foot taken in the plane of the axis of oscillation of the needle *x—x* Fig. 7, showing the needle penetrating the superimposed layer, and

Fig. 10 is a similar view showing the position of the needle when penetrating the base layer.

The usual type of sewing machine to which this improved presser foot is applied as shown in Fig. 1 comprises the base plate 1 from which rises the standard 2, carrying the usual arm which terminates in the head 3. The driving mechanism comprises the main shaft 4 which is suitably journaled in the sewing machine arm and carries adjacent its end suitable cams and gearing for actuating the stitch forming mechanism.

The stitch forming mechanism desirably comprises a curved needle 5 suitably sup-

- ported in a needle bar 6 which is pivotally mounted upon a shaft or stud 7 inclined to the plane of the base plate of the machine so that the plane of oscillation of the needle 5 is inclined to the vertical plane of the line of feed. The stud 7 upon which the needle bar oscillates desirably is supported by a link 8 which is pivotally mounted upon a shaft 9 in the upper portion of the sewing 10 machine head, suitable means such as an adjustable vibrating lever 10 being provided for oscillating the link 8 to cause the needle to vibrate alternately in different parallel planes as disclosed in my prior application 15 No. 830,788 filed April 9, 1914. Any desirable complementary stitch forming mechanism may be utilized with the curved oscillating needle aforesaid, as illustrated herein, it comprises a rotary hook 11 actuated by a train of gears 12, 13, a shaft 14, and worm gears 15, 16 suitably mounted in the head of the machine and the hook bracket carried thereby and driven from the main shaft of the machine. 20
- 25 As illustrated herein an upper feed dog 17 is provided which is carried upon the lower end of the vertically reciprocating and laterally oscillating link 18 provided with suitable actuating mechanism located in the 30 upper portion of the head of the sewing machine. A suitable lower feeding mechanism may be provided if desirable.
- Any suitable form of bender mechanism 35 may be utilized, such for example as that disclosed in my prior application aforesaid, and illustrated in Fig. 1, but inasmuch as the particular form of bender mechanism is inconsequential it will not be disclosed herein.
- 40 The presser foot which forms the main subject matter of the present invention desirably is secured to the under portion of the frame of the hook bracket by means of screws or other fastenings which enable it 45 to be maintained in a stationary position and coöperates in clamping the goods with a yieldable work support 19 which may be of the usual type.
- The presser foot illustrated herein 50 comprises a heel portion 20 having lateral wings 21, 22 of greater thickness than the central portion of the presser foot, the wings being provided with apertures 23 to receive the screws which secure the presser foot to the hook bracket.
- Toe portions 25, and 26 extend forwardly 55 from the heel portion and are adapted to rest respectively upon the base and the superimposed layers and coöperate in presenting the folded edge of the latter to the needle.
- The respective toe portions are provided 60 with slots 27, 28 to receive the upper feed dogs which engage respectively the base and superimposed layers. The major toe por-

tion 25, desirably may be made in two parts, one of which is integral with the heel portion and the other part 29 of which extends forwardly and may be secured to the integral portion by screws 30 or other fastenings. 70

A suitable edge guide 31 may be secured to the major toe portion by screws 32 as illustrated in Figs. 2, 7, and 8. The major toe portion 29 is adapted to rest upon the 75 base layer of the fabric and is inclined upwardly at its outer end in the usual manner to permit the fabric to be passed freely thereunder. The major toe portion is provided with a rearwardly extending needle 80 guiding member 33 which also forms a support for the under surface of the superimposed layer. The rearwardly extending portion 33 is cut away to form the needle throat 34 and is provided with a curved 85 needle guiding ledge or shoulder 35 which extends both in front and to the rear of the needle throat. A projection 36 extending forwardly from the heel portion lying adjacent to the end of the rearwardly extending member 33 is provided with a curved 90 needle guiding surface which further sustains the needle after its emergence from the fabric.

The under surface of the major toe member 95 is adapted to rest upon the base layer of fabric as above stated, the rearwardly extending member 33 being provided with a chamfered surface 37 on its under side to permit the base layer to be thrust upwardly 100 through the throat opening into the path of the needle when a stitch is to be formed in the base layer. The upper portion 38 of the rearward extension 33 is thickened and is provided with a curved upper surface as 105 illustrated in Figs. 9 and 10, the thickness of the member 33 diminishing toward its end in such a manner as to permit the goods to pass over the same and beneath the minor toe member 26 of the presser foot. 110

The under surface 39 of the major toe portion is offset and lies in a different and lower plane than the under surface 40 of the minor toe portion 26 (see Figs. 9 and 10). These surfaces are joined by an inclined shoulder 41 which serves as a guide for the superimposed layer after the same has passed the stitching point. The under portion of the minor toe member 26 is provided with a curved surface 42 complementary to the upper curved surface 38 of the major toe member so that as the superimposed layer is guided to the needle its upper surface is engaged by the surface 42 of the minor toe member while its under surface is engaged by the upper surface 38 of the major toe member, thus forming a positive controlling means for the surface which will prevent relative displacement of the plies of the superimposed layer and will 130

cause the edge to present a relatively loose fold in the path of the needle.

The edge of the superimposed layer is positively guided by the guide 31 in approaching the needle and by the shoulder 41 after passing the stitching point, so that by the coöperation of the edge and surface guides the superimposed layer is invariably presented to the needle properly.

10 The presser foot when secured in position upon the hook bracket is so located that the throat is well back of the vertical axial plane of oscillation of the needle whereby the needle will pass well beneath the overhanging edge *e*, (see Fig. 9) of the superimposed layer and will penetrate the superimposed layer well after its point has passed the vertical plane of its axis of oscillation and will emerge at a point nearer the edge 15 of the layer than the point in which it penetrates the same as illustrated in Fig. 7.

It will be understood that the form and proportion of the parts of the presser foot and its relation to the path of the needle 25 may be varied in accordance with the class of work for which the presser foot is adapted and that various changes and modifications may be made in the construction thereof within the scope of the claims hereto 30 annexed.

Having thus described my invention what I claim as new and desire to secure by Letters Patent is:

1. In a sewing machine for felling a superimposed layer of fabric upon a base layer comprising a curved needle oscillating in a plane inclined to the vertical plane of the line of feed, a presser foot having coöperating members provided with substantially parallel curved surfaces for guiding both the upper and under surfaces of the superimposed layer adjacent to the point at which the needle penetrates said layer.

2. In a sewing machine for felling a superimposed fabric upon a base layer comprising a curved needle oscillating in a plane inclined to the vertical plane of the line of feed, a presser foot having coöperating members provided with substantially parallel curved surfaces for guiding both the upper and under surfaces of the superimposed layer adjacent to the point at which the needle penetrates said layer and means for directing the edge of the superimposed layer both forward of the point of penetration and rearward of the point of emergence of the needle in said layer.

3. In a sewing machine for felling a superimposed layer of fabric on a base layer comprising a curved needle oscillating in a plane inclined to the vertical plane of the line of feed, a presser foot having coöperating members provided with substantially parallel longitudinally and transversely curved surfaces for guiding the upper and under sur-

faces of the superimposed layer adjacent to the point at which the needle penetrates said layer.

4. In a sewing machine for felling a superimposed layer upon a base layer of material comprising a curved needle oscillating in a plane inclined to the vertical plane of the line of stitching, a presser foot comprising a major toe portion adapted to rest upon the base layer and a minor toe portion 70 having an offset surface adapted to rest upon the superimposed layer, coöperating surfaces carried by said major and minor toe portions to engage respectively the upper and lower surface of the superimposed 75 layer and means carried by the major toe portion for guiding the needle.

5. In a sewing machine for felling a superimposed fabric upon a base layer comprising a curved needle oscillating in a plane inclined to the vertical plane of the line of feed, a presser foot having means for guiding both the upper and under surfaces of the superimposed layer adjacent to the point at which the needle penetrates said layer, and 85 positioned to cause the needle to penetrate said superimposed layer well after its point has passed the vertical plane of its axis of oscillation.

6. In a sewing machine for felling a superimposed fabric upon a base layer comprising a curved needle oscillating in a plane inclined to the vertical plane of the line of feed, a presser foot having means for guiding both the upper and under surfaces of 95 the superimposed layer adjacent to the point at which the needle penetrates said layer and positioned to cause the needle to penetrate the under surface of the superimposed 100 layer well back from the edge thereof and 105 to emerge therefrom at a point nearer the edge than that at which it entered said layer.

7. In a blind stitch sewing machine for felling a superimposed layer upon a base 110 layer comprising a work support, a curved oscillating needle and complementary stitch forming mechanism located above the work support; a presser foot having coöperating members extending longitudinally of the 115 direction of feed and provided with parallel surfaces transversely inclined to the plane of the work support adapted to engage the upper and under surface of the superimposed layer and to incline said layer so as 120 to present the under surface of said layer in the path of the needle whereby the needle will penetrate said under surface at a distance from the edge thereof and will emerge at a point at or beneath said edge.

8. In a sewing machine for felling a superimposed layer upon a base layer of fabric comprising a work support, a curved oscillating needle and complementary stitch forming mechanism located above said work sup- 130

port; a presser foot having coöperating guiding members provided with substantially parallel surfaces extending longitudinally in the direction of feed and inclined 5 transversely to the plane of the work support adapted to engage respectively the upper and under surface of the superimposed layer, the inner edge of the upper guiding member extending substantially parallel to 10 the inner edge of the lower guiding member and being located at a distance therefrom

whereby the edge of the superimposed layer will be presented in the form of a relatively loose fold in the path of the needle.

In testimony whereof, I have signed my 15 name to this specification, in the presence of two subscribing witnesses.

THOMAS J. HAYES.
